(57) **CLAIM**

The ornamental design for a support member for a tool mounting bar, as shown and described.

DESCRIPTION

FIG. 1 is a front perspective view of a support member for a tool mounting bar according to a first embodiment;

FIG. 2 is a right side view of the support member of FIG. 1;

FIG. 3 is a front view of the support member of FIG. 1;

FIG. 4 is a left side view of the support member of FIG. 1;

FIG. 5 is a top view of the support member of FIG. 1;

FIG. 6 is a rear view of the support member of FIG. 1; and,

FIG. 7 is a bottom view of the support member of FIG. 1.

The broken lines in the drawing depict boundaries of the

claim and form no part of the claimed design.
